ALFRED COPONY, OF CHICAGO, ILLINOIS, ASSIGNOR TO WILLIAM H. MINER, OF CHICAGO, ILLINOIS.

SINGLE-CENTER-SILL DRAFT-GEAR.

1,205,974.

Specification of Letters Patent. Patented Nov. 28, 1916.

Application filed January 12, 1914. Serial No. 811,623.

To all whom it may concern:

Be it known that I, ALFRED COPONY, a subject of the Emperor of Austria-Hungary, residing in Chicago, in the county of Cook 5 and State of Illinois, have invented a new and useful Improvement in Single-Center-Sill Draft-Gears, of which the following is a specification.

This invention relates to improvements in 10 single center sill draft gears.

Objects of the invention are to provide a draft gear for use in connection with cars having single center sills, the arrangement being such that the center line of the draft 15 gear coincides substantially with the center line of gravity of the center sill; to provide an arrangement whereby the ultimate or excessive shocks are transmitted directly to the center sill through cheek plates in the center 20 line of the gear and obviating the necessity of using a striking plate for the horn of the coupler to hit against, as has hitherto been customary; to provide a single center sill construction which extends from end to end 25 of a car and so braced and strengthened over the bolsters where the sill is cut out for the center plate that the centers of gravity at all sections through the center sill lie in substantially the same straight line; and in general 30 to provide a simple construction having high resistance to end shocks, having easy repair possibilities and eliminating the use of bolster center fillers and fillers between center sills.

35 The invention furthermore consists in the improvements in the parts and devices and in the novel combinations of the parts and devices herein shown, described or claimed.

In the drawing, forming a part of this 40 specification, Figure 1 is a side elevation of a construction embodying my improvements, the center plate and side members of the body bolster being shown in section and the drawing illustrating the center sill as far as 45 the center line only of the bolster, it being understood that the center sill is continuous from end to end of the car and is similarly constructed at both ends. Fig. 2 is a horizontal section taken on the line 2—2 of Fig. 50 1. Fig. 3 is a vertical sectional view taken on the line 3—3 of Fig. 1, and Fig. 4 is a longitudinal view of my improved center sill, the same being shown from end to end of the car but broken at the middle to pre-

vent crowding and the bolsters being shown 55 in section.

In said drawing A designates the single center sill which extends from end to end of the car and is of I form, having upper flanges 10, lower flanges 11 and web 60 12. The sill, at each end, is recessed or bifurcated, as shown at 13, and to the rear of each bifurcation the web is provided with two slots or recesses 14 and 15 through which extend, respectively, front 65 and rear followers 16 and 17. Riveted to the center sill on each side thereof and surrounding each of the recesses 14 and 15 are two cheek plates 18 in the form of steel castings, said cheek plates being provided with front 70 stops 19 and rear stops 20 for the followers. As shown most clearly in Fig. 2, a cap or wear-plate 21 may be secured over the forward ends of the cheek plates for a purpose hereinafter specified. The coupler B has its 75 draw-bar shank 22 slidably mounted within the bifurcation 13 and in normal position the rear or inner end 23 of the shank is spaced from the wear-plate 21 less than the horn 24 on the coupler is spaced from the steel 80 carry iron 25 which is also riveted to the center sill and is slotted as at 26 to provide sufficient clearance for the draw-bar so that the latter may swing from side to side when the car is rounding curves. Secured to the 85 draw-bar by means of a key 27 and bolt 28 are two yoke arms or spring pocket members 29, each of which is provided with a substantially rectangular recess 30 through which extend the followers 16 and 17. Between the followers and on opposite sides of the center sill in twin arrangement are two sets of nested springs 31, 31, the springs being mounted on bolts 32 which extend through the followers and the yoke arms. 90 Thimbles 33 are also mounted on said bolts between the followers to assist in supporting the springs.

From the preceding description, it will be seen that I have provided a twin-arranged 100 spring draft gear for a single center sill construction in which the forces transmitted from the draft arms to the followers are applied to the latter directly in line with the springs, a desirable result inasmuch as it relieves the followers of bending strains. Furthermore, on account of the inner end of the draw-bar shank being nearer the wear- 105

plate 21 than the coupler horn 24 is to the 45
carry iron, the final or excessive shocks will
be transmitted directly to the center sill in
the line of its center of gravity through the
5 cheek plates 18 and the resistance to such
shocks is distributed simultaneously through
all the rivets which extend around the cheek
plates and connect the latter to the center
sill. This arrangement renders it unneces-
10 sary to employ a striking plate. Hitherto it
has been the common practice to provide for
the ultimate or excessive shocks by transmit-
ting the same through the coupler horn to
the striking plate, which, as will be ap-
15 parent, transmits the shock to the center sill
eccentrically or out of alignment with the
center line of gravity thereof.

In order to allow for the proper height of
the floor from the top of the railing, the cen-
20 ter sill is necessarily cut out over the bolster
as indicated at 34. To maintain the center
of mass of any vertical section of the center
sill over the bolster in line with the centers
25 of mass of any similar section of the center
sill anywhere throughout its length, I attach
to the center sill, adjacent each cut out portion
over the body bolster, a casting or rein-
forcement 35 each of which is constructed
30 and designed substantially as shown in the
drawing, the disposition of the metal thereof
being so calculated that the center of mass
of any vertical section taken through the
center sill and said casting will be substan-
35 tially in line with the center of mass of any
other vertical section of the center sill. The
cast steel reinforcement 35 is also so ar-
ranged that the side members 36 of the
bolster may be riveted thereto and also the
40 center plate 37, thus doing away with any
bolster center fillers or fillers between the
center sills. As will be understood, the cen-
ter sill between the bolsters is left intact.

From the foregoing description, it will be
seen that by maintaining the center of

gravity of the center sill where it is cut out 45
over the bolsters in line with the center line of
the draft gear and center of gravity of the
rest of the center sill, all the shocks are ab-
sorbed in the most efficient manner by the
center sill and eccentric transmission of any 50
of the shocks to any part of the center sill
is avoided.

Although I have herein shown and de-
scribed what I now consider the preferred
embodiment of my improvements, yet it will 55
be understood that various changes and
modifications may be made without depart-
ing from the spirit of the invention, and all
such changes and modifications are contem-
plated as come within the scope of the claims 60
appended hereto.

I claim:

1. In a car, the combination with a single center sill extending from end to end of the car, said center sill being recessed over the 65 bolsters and reinforced with steel castings around said recessed portions, the reinforcing castings being so designed that the center of mass of a vertical section of the center sill over the bolsters is substantially in line 70 with the center line of mass of all similar sections of the sill throughout its remaining portions, the ends of the center sill being bifurcated.
2. In a car, a single center sill extending 75 from end to end of the car, each half of said center sill being recessed over the bolster and bifurcated at its end and having a cast rein-
forcement secured thereto at the portion 80 where it is recessed for the bolster, substan-
tially as specified.

Signed this 8th day of January, 1914, in
the presence of two witnesses.

ALFRED COPONY.
